UNITED STATES PATENT OFFICE.

CHARLES W. RUGG, OF CAMBRIDGE, MASSACHUSETTS.

STEAM-HEATING APPARATUS.

SPECIFICATION forming part of Letters Patent No. 348,932, dated September 7, 1886.

Application filed September 30, 1885. Serial No. 178,663. (No model.)

To all whom it may concern:

Be it known that I, CHARLES W. RUGG, of Cambridge, in the county of Middlesex and State of Massachusetts, have invented certain new and useful Improvements in Steam-Heating Apparatus, of which the following is a full, clear, and exact description.

This invention relates to that class of steam-heating apparatus in which separate combustion-chambers or fire-boxes are employed, having communication with each other, and each separately connected with the chimney or escape-flue, and each of said connections provided with a damper, both preferably connected and arranged to be opened and closed from one operating mechanism, so as to secure the closing of either damper on the opening of the other, and vice versa, and all so that the products of combustion from either fire-box or chamber may be caused to pass into and through, and thus made to commingle with, the products of combustion in the other fire-box and thence to the chimney or flue common to both fire-boxes. Apparatuses of this class are to be found shown and described in various Letters Patent of the United States heretofore issued, among them, notably, the following: Letters Patent to Henry Wilkins, October 3, 1860, No. 30,275; A. J. Bell and J. P. Friend, December 24, 1872, No. 134,243; D. Argerbright and W. Allensworth, January 25, 1875, No. 159,141; R. L. Walker, July 25, 1876 and July 11, 1882, Nos. 180,178 and 260,810, to either or all of which reference is hereby had for a better understanding thereof.

The present invention pertains, particularly, to the arrangement of the water apparatus, and its combination with fire-boxes or combustion chambers, of a construction, arrangement, and operation, substantially such as described; and its object is to obtain the most efficient results in the heating of water and generation of steam therefrom with the least possible expenditure of fuel, and to secure an active circulation of the water to insure the most perfect combustion, and otherwise to render the apparatus serviceable and useful to the highest degree for the purposes stated.

To this end the invention consists, in substance, in the disposition in, and so as to sur-

round, the walls of the upper portion, either one or both, (preferably both,) of such combustion-chambers or fire-boxes, preferably made of a dome shape, and above the fuel or fire-chamber proper thereof, of a coil of pipe 55 having its several coils separated from each other, so that the products of combustion from the burning fuel below can freely circulate about them, and each coil between or at its upper and lower ends connected to a common 60 closed drum that is located in another and separate chamber or compartment having communication, but by separate passages, each provided with a damper for opening and closing it, with the upper portion of each of said 65 combustion-chambers and by a common passage with the chimney or flue, said drum being suitably adapted for the entrance of water thereto and for the escape of steam therefrom, and all substantially as hereinafter described. 70 -

In addition to the above, this invention consists of a closed drum arranged within a closed chamber or compartment of suitable construction, which has communication with a chimney or flue, and is adapted for water to be 75 entered into and the steam to escape from it, and of a series of combustion-chambers or fire-boxes, each preferably made of a dome shape, arranged about and each at its upper portion, but by separate passages, each provided with a damper for opening and closing it, in communication with said drum-containing compartment, and also adapted for communication with each other in pairs, and so that the products of combustion of either one 85 of the pairs of said so-communicating combustion-chambers can pass into and through and commingle with the products of combustion of the other, and vice versa, in combination with a vertical coil of pipe located in the upper and dome-shaped portion of either one or both of said combustion-chambers of each pair and above the fuel or fire chamber proper thereof, and having its several coils separated from each other, so that the products of combustion from the burning fuel below can freely circulate about them, and each of so-located coils between or at its upper and lower ends connected to the said closed drum, all substantially as hereinafter described. 95 -

In the accompanying drawings, forming a part of this specification, a steam-generating apparatus of the present improved construction and combination of parts is illustrated.

5 Figure 1 is a section crossing through the center of the drum-containing compartment and of a combustion-chamber or fire-box on opposite sides thereof, and an elevation of said drum, and of a coil in each of said fire-boxes, 10 both connected to said drum, and in other of the parts of the apparatus in vertical section or elevation, as the case may be, and as the same fully appears on inspection. Fig. 2 is a section on a horizontal plane of the drum-containing 15 compartment and of its drum, and of four combustion-chambers or fire-boxes arranged in regular order around said drum-containing compartment, and a plan view of the remainder of the apparatus, and in which is located 20 two more combustion-chambers or fire-boxes following and in regular order, with its similar chambers shown in horizontal section, as aforesaid, and in other of the parts of the apparatus in horizontal section or plan view, as the 25 case may be and as the same fully appears on inspection. Fig. 3 is a vertical section on line 3 3, Fig. 2.

In the drawings, A A², B B², and C C² represent a series of vertical combustion-chambers or fire-boxes arranged in regular order about a common central and vertical compartment or chamber, D, which extends above them. Each combustion-chamber is of a cylindrical form and dome-shaped at its upper end or portion, E, and, again, each is provided with a feed-door, F, for fuel, a pit, G, for ashes, having door H, and a fire-grate, J, between the ash-pit G and feed-door F, and otherwise each is suitably built and constructed for the combustion of fuel—such as coal—and in any of the well-known ways of construction—as, for instance, as to its walls K, doors F and H, fire-grate J, floor M to ash-pit, and the same is true as to the walls of the compartment D, 45 about which the aforesaid several fire-boxes or combustion-chambers are arranged, and therefore needing no further description herein, except as the same is necessary for a perfect understanding of the features of this invention.

50 N is a vertical cylindrical and closed metal drum located in the compartment D, and standing and supported upon a base, O, resting on the floor P of said compartment. An open space is left around all parts of the drum, 55 and the drum at its lower end, by a suitably-attached pipe, P², has communication with a water-supply, and at its upper end by a suitably-attached pipe, Q, with the apparatus, heating or otherwise, in which the steam generated from the apparatus of this invention, as will hereinafter appear, is to be used.

The water-level of the drum N, as it is shown, is at R, Fig. 1.

S is a vertical coil of metal pipe located in 65 the upper and dome portion, E, of each of the combustion-chambers or fire-boxes A A², B

B², and C C², and of a shape vertically and horizontally corresponding to and surrounding said dome portion E. The coils of each coil S are separated from each other and from the walls of the dome portion E of the combustion-chamber, in which each coil S is placed. Each coil S is above the fire or fuel part proper of its combustion-chamber, and which is at T; and, again, the upper and lower coil 70 of each of the coils S is connected by horizontal extensions U and V, respectively, thereof, with the drum N in the compartment D, and both of such connections, as shown, are below the water-level R of said drum; but the upper 75 connection may be on a level with or above the said water-level. The combustion-chambers aforesaid have communication with each other in pairs, by means of an opening, W, in the dividing-wall thereof, and these several openings, of which there are three, in the arrangement of said chambers, as they are at present illustrated, are arranged in the same horizontal plane, and in a plane below the lower end 80 of the coil S, and at or about the fuel-level of 85 each combustion-chamber.

X is a passage leading from the upper end of such combustion-chamber and entering into the upper end of the compartment D, containing the drum N. Each pipe X has a 90 damper, Y, arranged in the ordinary or in any suitable manner, to be operated from the outside to open and close the passage of its pipe; but, as shown in the drawings, these dampers are adapted in pairs corresponding to the combustion-chambers, as they are adapted in pairs for communication with each other, as aforesaid, to be operated from one common operating-rod, Z, joining the two and provided with a handle, D², suitably and conveniently 100 arranged, and so that in moving said rod in one direction the damper connected to it, of one passage, will be opened, and the damper of the other passage closed, and in moving it in the other and opposite direction the damper 105 which was before opened will be closed, and the other, which was before closed, will be opened.

E² is a passage leading from the bottom of the compartment D, containing the drum N. 110 This passage is to be connected at F² in any suitable manner to a chimney or escape-flue. (Not shown.)

In an apparatus, such as has been above described, embracing three pairs of combustion and communicating chambers or fire-boxes, A A², B B², and C C², arranged about and having a communication, each capable of being regulated by a damper, Y, with a common compartment, D, containing a drum, N, having 120 water and steam communication P and Q, and each provided with a coil, S, connected with said drum N, and compartment D, connected with the chimney or flue, it is plain that with 125 combustion going on in all of said combustion-chambers the products of each thereof on their way to the chimney or escape-flue first 130

circulate within and through their respective combustion-chambers about the coils thereof, and from one to the other of each pair through their communicating opening W, according as the dampers of said so-communicating chambers are adjusted, and then pass from the combustion-chamber of each pair which is open to the compartment D, containing the drum N, into the upper portion of said compartment D, and thence downward about and around said drum N and out at the passage E² in the lower portion of said compartment to the chimney. Under this operation plainly the water within the separate coils S and the drum N, common to and in communication with them all, necessarily becomes heated, and, if the several fires are properly run, generated into steam, and which has its escape at the steam-pipe Q of the drum, to be utilized as intended, causing, as is plain, a circulation of water from the water-supply connected at P through the drum N and coils S, to take the place of the water so made into steam, and the whole producing, under a proper operation and manipulation of the apparatus described, and a utilization of the communicating pairs of combustion-chambers, in the manner of which combustion-chambers so connected are capable of being utilized, as is well known, a most active circulation of water through and generation from the water of steam in the coils S and drum N, and in a most effective and economical manner as to the amount of fuel required, and other respects.

Results similar to those above stated, but varying, of course, in degree, will be secured by either a reduction from or increase in the number of pairs of combustion-chambers constructed and arranged and provided and combined, as has been described, for the three pairs A A², B B², C C² of such chambers. Again, by giving the upper portion of each combustion-chamber a dome shape, and arranging therein and adapting thereto a coil of water-circulating pipe, as has been described, plainly the efficiency of the apparatus is increased, for the reason that the heat and products of combustion are the better concentrated about and around the separate coils of each coil S of pipe; but the dome may be dispensed with, and still secure good and effective results under the combination and arrangement of combustion-chambers in pairs communicating with each other, and with a common compartment having a water-drum connected with a coil, S, of water-pipe arranged in either or both of said chambers and otherwise, all as has been described. More or less coils of pipe may be arranged in each combustion-chamber, all, however, connected with the common drum N either directly or through each other.

In my patent of August 19, 1884, No. 303,667, I have shown a grate and steam-heating devices consisting of two coils with an annular water-heating chamber between them,

all arranged in a combustion-chamber and communicating with a reservoir in a separate chamber, through which the products of combustion are carried. I claim in this application nothing shown and described in said Letters Patent.

My present invention differs from the construction shown in my above-named patent in comprising one or more pairs of intercommunicating combustion-chambers communicating with a central compartment, which encloses a drum, only one coil being arranged in each combustion-chamber, and said coils being in communication at both ends with the drum in the central compartment.

In my former patent an intermediate chamber is located between the combustion-chamber and drum-chamber, and this intermediate chamber I have dispensed with by my present invention. I have also provided separate passages through which the intercommunicating combustion-chambers can communicate direct with the drum-compartment or be shut off therefrom by means of dampers connected in pairs so arranged that when one is opened the other will be closed. This arrangement of directly intercommunicating combustion-chambers, each of which also communicates by a separate passage with the drum-compartment, said passages being provided with dampers operating as described, and each combustion-chamber containing a single coil communicating at both ends with the central drum, enables the apparatus to be more readily controlled and effects the most advantageous results in attaining a perfect combustion and increased production of heat.

Having thus described my invention, what I claim, and desire to secure by Letters Patent, is—

1. In combination, a pair of combustion-chambers, such as A A², communicating with each other, and a coil or coils, S, of water-pipe, a compartment, D, having a drum, N, with water and steam connections, and connected to said coil or coils, separate passages X, each having a damper, Y, and connecting said combustion-chambers with said compartment D, substantially as described, for the purpose specified.

2. In combination, a pair of combustion-chambers, such as A A², communicating with each other, and each of dome shape in its upper portion, a coil or coils, S, of water-pipe arranged in the dome of said chambers, a compartment, D, having a drum, N, with water and steam connections and connected to said coil or coils, and separate passages X, each having a damper, Y, and connecting said combustion-chambers with said compartment D, substantially as described, for the purpose specified.

3. In combination, a series of pairs of combustion-chambers, such as A A², the members of each pair communicating with each other and provided with a coil or coils, S, of water-pipe,

a compartment, D, having a drum, N, with water and steam connections and connected to said coil or coils, and separate passages X,
each having a damper, Y, and connecting said
5 combustion-chambers with said compartment D, substantially as described, for the purpose specified.

In testimony whereof I have hereunto set my hand in the presence of two subscribing witnesses.

CHARLES W. RUGG.
